UNITED STATES PATENT OFFICE

STEPHEN ANDRÉ BRANDON, OF FRESNAY-SUR-SARTHE, FRANCE

MACHINE FOR CUTTING RIBBONS FROM BIAS OR STRAIGHT-WOVEN TEXTILE FABRIC,
LEATHER, RUBBER, OR OTHER SIMILAR MATERIALS

Application filed July 22, 1926, Serial No. 124,275, and in France December 29, 1925.

The present invention relates to improvements in machines for cutting ribbons, whether of fabric, leather, rubber or other similar materials, which machines are most generally used in the manufacture of bias-textile ribbons. It is often necessary that the bias-portions of fabric used in dressmaking, millinery and the like shall have a certain length, but when these biases are cut by hand in the piece of fabric, it is evident that their length cannot be greater than that of the bias taken from one selvedge to the other of the fabric and this length, of course, may vary according to the width of the fabric. In order to obtain bias-pieces of a relatively considerable length it is necessary to sew a certain number of bias-pieces to each other; but this operation is time-consuming and expensive, so that, with a view to expediting the work and reducing the cost thereof, it has been proposed to cut, out of the fabric, strips bounded on the one hand, by the selvedges of the fabric and on the other hand by two parallel inclined or biased cuts which are spaced apart about one meter and to unite, by a seam, the two selvedges of the piece of fabric cut in this way. A tubular piece of fabric is thus obtained the basic circumferences of which are biased. The cutting of the bias piece is effected along one of these bases, one of the edges of the fabric being displaced longitudinally of the edge upon which it is sewn, by an amount equal to the width of the bias-piece which is to be obtained, so that this bias-piece can be cut along a spiral so as to enable a bias-ribbon to be obtained, which is continuous from one end to the other of the tubular piece of fabric (see French Patent No. 564,008 of March 17, 1923). It would be difficult and troublesome to effect this cutting operation by hand, so that a machine has been designed and constructed, which can be driven either mechanically or by hand, and which effects this cutting operation by means of a rotary knife, the fabric being guided by the operator himself so as to present it to the knife. Machines of this kind comprise, apart from the rotary knife which is driven by the actuating mechanism of the machine, two feed-rolls upon which is mounted the tubular piece of fabric which is to be

cut, one of said rolls being cylindrical, while the other is conical so as to permit of the entrainment of the fabric towards the knife, these two rolls being rotated in the same direction but in the opposite direction to the knife. A guide is arranged in front of the knife and carries bars which are parallel to each other and between which the edge of the fabric is slid with an undulating movement so that it is held in a suitable manner against the guide. A spool is mounted in the rear of the rotary knife and is driven by a transmission mechanism from the driving gear of the machine, whereby it is possible to wind up the ribbon as it is cut.

It is evident that this machine gives a considerable degree of efficiency, but the guiding means with which it is provided are not sufficient to ensure a uniform entrainment and a uniform cut of the fabric. In addition the constant presence of an attendant is necessary in order that he may frequently rectify the position of the edge of the fabric to be cut and prevent the fabric itself from sliding longitudinally upon the feeder-rolls, either too rapidly or too slowly. If the speed of entrainment is too great, pleats will be formed on the edge of the fabric near the knife and the guide, whereas if the feed is too slow the edge of the fabric does not come satisfactorily into contact with the guide, and the cut in either case presents irregularities.

The present invention relates to improvements in machines for cutting ribbons or strips of fabric or other material (strips of fabric having the threads at an angle or straight, rubber, leather and the like) the purpose of these improvements being to increase the efficiency and speed of the machine by reducing to a great extent the necessity for supervision of the feed of the fabric or other material, to ensure a normal feed and a uniform cut, to enable tubular fabric of relatively large width to be cut upon a machine of small capacity, and to enable the cut strip to be turned in, especially in the case of bias-strips, depending upon the form in which the strips are employed in the millinery, dressmaking and clothing industries, as they are cut and before they are rolled up.

The invention consists in providing the machine with means for diminishing fitfully the width of the extremity of the tubular article which is furthest away from the guide and from the knife, so that this tubular fabric shall have a tendency to advance longitudinally upon the feed rolls towards the guide.

According to one embodiment of the invention, these means comprise a deflecting rod mounted beneath the table of the machine and capable of oscillating horizontally so as to push back to a greater or less extent the portion of material held by the front feed roll 10 towards the portion of material held by the rear feed roll, the action of this deflecting rod diminishing in intensity towards the knife.

The invention also consists in combining, with this deflecting rod, a second deflecting rod arranged almost parallel with the former, and mounted upon a bar which can pivot thereabout so that, when the portion of material is inserted between the two deflecting rods, a more efficacious action upon the fabric is obtained by the rotation of the bar around the first rod, the bar itself constituting a preliminary lateral guide member for the edge of the fabric before it reaches the guide arranged in front of the knife.

30 The invention also consists in providing a supplementary deflecting-rod, shorter in length than the other deflecting-rods, so as to enable it to exert its action upon the end of the tubular piece when this latter comes into proximity with the guide and the knife.

The invention also consists in arranging two deflecting-rods parallel one to the other and enabling their longitudinal movement to be effected by the operation of a wheel so 40 that once the material is inserted between them, they feed the said material in a uniform manner towards the guide and the knife.

The invention also consists in mounting the 45 deflecting-rods in such a manner that they are fixed and parallel to each other, and to the plane of the fabric, a bar being arranged between them either parallel or obliquely, the said bar being able to move in a horizontal plane perpendicularly to the edge of the fabric.

The invention furthermore consists in mounting at the front of the machine an arm oscillating freely around a vertical shaft and bent at its free end so that it can be introduced between the fabric and the folded-back extremity of this latter, this arm serving to unfold the extremity of the fabric in accordance 55 with its advancing movement upon the machine.

In the drawing:—

Fig. 1 is a front elevation of a machine for cutting ribbons of any material (biased or 60 ordinary fabric, leather, rubber and the like)

embodying the improvements forming the subject of the present invention.

Fig. 2 is a corresponding plan view.

Fig. 3 is a side view.

Fig. 4 is a section along line IV—IV of Fig. 2.

Figs. 5 and 6 represent diagrammatically the method of action of the deflecting rods.

Fig. 7 shows diagrammatically the method of action of the unpleating arm.

Figs. 8 and 9 show a modified form of construction of the deflecting-rods.

Figs. 10 and 11 show another modified form of the deflecting-rods.

Referring to the drawings:

The machine comprises a table 1 mounted upon a frame 2, said table carrying the various mechanisms necessary for actuating the machine and for the feeding, guiding, and cutting of the fabric. The rear feed-roll 6 is keyed upon the shaft 3 of the pulley 4 which is mounted in suitable bearings 5. This feed-roll 6 is of conical form and its movement is transmitted to the front feed-roll 7 by means of pulleys 8 and 9 and of the belt 10. The frame F is provided with a slot S to enable the tubular fabric to be threaded engaged from the left of the machine over the rolls 6 and 7 and between the rolls 15 and 16. The slot S is substantially level with the top of the feed roll 6.

The tubular piece of fabric to be cut is mounted upon these feed-rolls 6 and 7.

The rotary knife 11 is mounted upon a shaft 12 which is driven from shaft 3 through the intermediary of toothed wheels 13 and 14, said shaft being provided with a rubber cylinder 15 which bears against a cylinder 16 of the same material mounted upon the rear feed-roll 6. Cylindrical rods 17 and 18 rotating freely upon their axes are arranged respectively in the rear of the front roll 7 and in front of the rear roll 6, so as to facilitate the sliding movement of the material upon these rolls and assist in its transversal movement.

The guiding of the edge of the fabric towards the knife is effected by a vertical blade 19 carrying small bars 20 and 33 by which the edge of the fabric is engaged alternately in such a manner as to ensure efficient guiding of the edge of the fabric into contact with the guide. The periphery of the bar 20, which lies nearest to the rotary knife 11, may, as shown in Figure 2, be roughened in order to prevent the fabric, as it passes over said bar, from becoming displaced longitudinally of said bar. The yoke-like member Y (Figs. 1, 2 and 3) forms part of a device serving to regulate the pressure of the cutting blade 11 against the counter-roll 16. The said regulating device is well known and forms no part of the present invention.

A take-up spool for the bias-strip of fabric is arranged in the rear of the knife 11. This spool 44 is pressed by a spring 45 upon

a rubber cylinder 46 which serves to drive it, and which itself is driven from the shaft 3 by a belt transmission 47. The drawbacks inherent to the machine so far described will be evident from this brief description. The fabric is engaged by the two feed-rolls 6 and 7, the first of which is tapered so as to assist in feeding it longitudinally towards the knife and it therefore advances in an irregular manner in this direction and overlaps the guide 19 or moves too far away therefrom so that the operator is obliged to constantly bring back the edge of the fabric to maintain it just in contact with the guide. Furthermore, when the machine receives a tubular piece of fabric of width superior to the length of the machine, the extremity of the fabric is folded upon itself, and it is necessary to remove this pleat by hand when it approaches the knife.

Furthermore, the edge of the fabric during its transverse movement towards the knife is drawn too forcibly towards the guide, with the result that it does not always pass along this latter as accurately as is desirable.

Finally, the insertion of the edge of the fabric alternately above and below the bars 20 and 33 of the guide 19 is somewhat difficult.

The improvements now to be described have been devised to obviate these various drawbacks.

With a view to ensuring a uniform longitudinal feed of the fabric towards the knife, a deflecting rod 22 is mounted upon a vertical shaft 21 fixed to the table 1 of the machine, which deflecting rod 22 can oscillate horizontally. Furthermore, a bar 23 is fixed upon this deflecting rod 22 in an adjustable manner and a supplementary deflecting-rod 25 is held in this bar 23 by means of a nut 24, the deflecting bar 25 being arranged almost parallel to the deflecting rod 22 and being mounted in such a manner that it can oscillate about the said deflecting rod 22 by the rotation of the bar 23. An adjustable support 26 is mounted upon the shaft 21 and carries a deflecting-rod 27 which is shorter than the deflecting-rod already mentioned.

Assuming the tubular fabric is engaged in the machine as described above and the various rolls rotate, if the roll 6 is conical, as shown, the rod, if parallel to the axis thereof, will increase the natural tendency of the tubular fabric to ride up the portion of largest diameter of the roll. The same effect occurs in belt transmissions, where the pulleys are always barrel shaped. If the rod 63 is angularly arranged with respect to the longitudinal direction of the tubular fabric, it will obviously deflect the whole of the fabric longitudinally (as if it were an endless belt hanging from a rotating transmission drum) and cause it to move toward the

non-deflected end of the tubular fabric (toward the right on the drawing).

The tubular piece of fabric 28 being mounted upon the rolls 6 and 7 as shown diagrammatically in Figs. 5 and 6, the deflecting rod 22 is caused to pivot about its axis 21 before starting the machine, so that its extremity deflects the extremity of the material inwardly as shown in Fig. 5, the result of this being to force the fabric to move towards the guide 19. The advancing movement of the fabric in the longitudinal direction can be varied by setting this bar 23 at a greater or lesser angle relative to the axis of the rolls 6 and 7. It would also be possible to exert a certain tension upon the tubular fabric with a view to rendering the advancing movement of the fabric more regular, care being taken to pass the material between the rods 22 and 25 and by causing the latter rod to oscillate to a greater or less extent about the deflecting rod 22 as indicated in Fig. 6. The rod 27 plays the same part as the deflecting rod 22 as regards the fabric, but only when it is advanced to a sufficient extent to be out of the range of action of the said deflecting rod 22.

The deflecting rods can evidently be arranged in a different manner to that shown and described, while at the same time assisting in the longitudinal feeding or entrainment of the tubular fabric.

For example, the deflecting rods 22 and 25 instead of oscillating about the vertical axis 21 could move longitudinally so as to ensure the longitudinal entrainment of the fabric once the latter has been inserted between them.

In this case, as can be seen from Fig. 8, the two deflecting rods 22' and 25' would be mounted upon a cross-piece 51 which in turn would be mounted to oscillate about the extremity of a rod 52 of angular cross-section and screw-threaded at its end, this rod being capable of longitudinal movement in its support 54 of corresponding cross-section, without rotating upon itself, under the action of a hand-wheel 53 which is held in position upon the support 54. By suitably inclining the cross-bar 51 the material can be held firmly so as to ensure its entrainment (see Fig. 9) and by longitudinally adjusting the rod 52 by means of the hand wheel 53 it is possible to vary the feed of the material according to the width of the bias to be cut.

The rods 22'' and 25'' could also be arranged as shown in Figs. 10 and 11; in this case the deflecting action upon the fabric would be exerted by a bar 55 arranged either parallel or obliquely relative to the rods 22 and 25 and capable of moving in a horizontal plane so as to push back the fabric 28 as shown in Fig. 11.

In order to place tubular pieces of fabric of large width in working position upon

this machine without increasing its overall dimensions, there is provided an arm 29 which can oscillate upon an axis 30 carried by the table 1, this arm being bent as shown at 31 in Fig. 2. When the width of the tubular fabric 28 being operated upon is greater than the length of the feed-rolls 6 and 7, the extremity of the tubular piece remote from the cutting line is folded upon itself and the inclined extremity 31 of the arm 29 (see Fig. 10 7) is introduced between the tubular piece 28 and the fold 32.

As the tubular piece advances longitudinally towards the guide, the bent portion 31 of the arm 29 pushes back the fold and deforms it, the action of the arm 29 being greatly facilitated by the freedom of its oscillation about its axis 30.

I claim:

20 1. A machine for cutting bias pieces from a tubular fabric, comprising front and rear feed rolls for threadedly receiving the fabric, a knife for cutting said bias pieces from the advancing edge thereof, a guide for the fabric, a rod pivoted at one end and arranged to engage and urge the material passing over the front feed roll towards the material passing over the rear feed roll and to deflect the material toward said guide.

30 2. A machine for cutting bias pieces from a tubular fabric comprising front and rear feed rolls for threadedly receiving the fabric, a knife for cutting said bias pieces from the advancing edge thereof, a guide for the fabric, a rod pivoted at one end and arranged to engage and urge the material passing over the front feed roll towards the material passing over the rear feed roll to deflect it toward said guide, and a second rod between which 40 and the first-mentioned rod the material can be inserted.

35 3. A machine for cutting bias pieces from a tubular fabric, comprising front and rear feed rolls for threadedly receiving the fabric, a knife for cutting said bias pieces from the advancing edge thereof, a guide for the fabric, a rod pivoted at one end and arranged to engage and urge the material passing over the front feed roll towards the material passing 50 over the rear feed roll to deflect it toward said guide, and a second rod between which and the first-mentioned rod the material can be inserted, said second rod being pivotally mounted relative to said first rod.

55 4. A machine for cutting bias pieces from a tubular fabric, comprising front and rear feed rolls for threadedly receiving the fabric, a knife for cutting said bias pieces from the advancing edge thereof, a guide for the fabric, a rod pivoted at one end and arranged to engage and urge the material passing over the front feed roll towards the material passing 60 over the rear feed roll to deflect it toward said guide, and a second rod cooperating 65 with said first rod, said rods being ad-

justable to insure uniform motion of the material towards the guide and the knife.

5. A machine for cutting bias pieces from a tubular fabric, comprising front and rear feed rolls for threadedly receiving the fabric, 70 a knife for cutting said bias pieces from the advancing edge thereof, a guide for the fabric, a rod pivoted at one end and arranged to engage and urge the material passing over the front feed roll towards the material passing over the rear feed roll to deflect it toward said guide, a second rod cooperating with said first rod, said rods being adjustable to insure uniform motion of the material towards the guide and the knife, and a bar arranged between said rods for pushing back the fabric. 75

6. A machine for cutting bias pieces from a tubular fabric, comprising front and rear feed rolls for threadedly receiving the fabric, 80 a knife for cutting said bias pieces from the advancing edge thereof, a guide for the fabric, a rod pivoted at one end and arranged to engage and urge the material passing over the front feed roll towards the material passing over the rear feed roll to deflect it toward said guide, a second rod cooperating with said first rod, said rods being adjustable to insure uniform motion of the material towards the guide and the knife, and a bar arranged between said rods for pushing back the fabric. 85

7. A machine for cutting bias pieces from a tubular fabric, comprising front and rear feed rolls for threadedly receiving the fabric, 90 a knife for cutting said bias pieces from the advancing edge thereof, a guide for the fabric, a rod pivoted at one end and arranged to engage and urge the material passing over the front feed roll towards the material passing over the rear feed roll to deflect it toward said guide, a second rod cooperating with said first rod, said rods being adjustable to insure uniform motion of the material towards the guide and the knife, and a bar arranged between said rods and parallel thereto for pushing back the fabric. 95

100 8. A machine for cutting bias pieces from tubular fabrics, comprising front and rear feed rolls for threadedly receiving the fabric, a knife for cutting said bias pieces from the advancing edge thereof, a guide for the fabric, two rods arranged parallel to each other and each pivoted at one end and arranged to engage and urge the material passing over the front feed roll toward the fabric passing over the rear feed roll to deflect the material toward said guide, and a third deflecting rod of less length arranged to guide the fabric when in proximity with the knife. 110

115 9. A machine for cutting bias pieces from tubular fabrics, comprising front and rear feed rolls for threadedly receiving the fabric, a knife for cutting said bias pieces from the advancing edge thereof, a guide for the 120

5 fabric, a rod pivoted at one end and arranged to engage and urge the material passing over the front feed roll towards the material passing over the rear feed roll to deflect it toward said guide, a second rod cooperating with said first rod, and means for setting said second rod at a greater or smaller angle relative to the axes of the feed rolls.

10 10. A machine for cutting bias pieces from tubular fabrics, comprising front and rear feed rolls for threadedly receiving the fabric, a knife for cutting said bias pieces from the advancing edge thereof, a guide for the fabric, and two rods arranged parallel to 15 each other and each pivoted at one end and arranged to engage and urge the fabric passing over the front feed roll toward the fabric passing over the rear feed roll to deflect the material toward said guide, said 20 rods being adjustable to vary the feed of the fabric.

11 11. A machine for cutting bias pieces from tubular fabrics, comprising front and rear feed rolls for threadedly receiving the fabric, a knife for cutting said bias pieces from the advancing edge thereof, a guide for the fabric, two rods each pivoted at one end and arranged to engage and urge the fabric passing over the front feed roll toward the 25 fabric passing over the rear feed roll to deflect the material toward said guide, and a bar located between said two rods and arranged to push the fabric for the purpose set forth.

30 35 12. A machine for cutting bias pieces from tubular fabrics, comprising front and rear feed rolls for threadedly receiving the fabric, a knife for cutting said bias pieces from the advancing edge thereof, a guide for the fabric, two rods each pivoted at one end and arranged to engage and urge the fabric passing over the front feed roll toward the fabric passing over the rear feed roll to deflect the material toward said guide, and a bar located adjacent said rods and arranged to 40 45 push the fabric for the purpose set forth, said bar being arranged obliquely to said rods.

50 55 13. A machine for cutting bias pieces from tubular fabrics, comprising front and rear feed rolls for threadedly receiving the fabric, a knife for cutting said bias pieces from the advancing edge thereof, and a guide for the fabric, said guide having two sets of bars over and beneath which the fabric passes, the periphery of the bar nearest to the knife being roughened.

STEPHEN ANDRÉ BRANDON.
